RANDOLPH CROMPTON, OF WORCESTER, MASSACHUSETTS, ASSIGNOR TO RANDOLPH CROMPTON, GEORGE CROMPTON, EDWARD D. THAYER, AND WILLIAM B. SCOFIELD, OF WORCESTER, MASSACHUSETTS.

SHEDDING MECHANISM FOR LOOMS.

SPECIFICATION forming part of Letters Patent No. 770,168, dated September 13, 1904.

Application filed June 7, 1904. Serial No. 211,526. (No model.)

To all whom it may concern:

Be it known that I, RANDOLPH CROMPTON, a citizen of the United States, residing at Worcester, county of Worcester, and State of Massachusetts, have invented an Improvement 5 in Shedding Mechanism for Looms, of which the following description, in connection with the accompanying drawings, is a specification, like letters on the drawings representing like parts.

This invention has for its object to improve the class of shedding mechanism represented in United States Letters Patent No. 397,858, dated February 12, 1889.

15 The particular feature comprising the invention to be herein described and claimed is comprehended in a series of elbow-levers adapted to ride on the upper edges of the connectors uniting the vibrator-gears with the harness levers or jacks and means for simultaneously turning said elbow-levers to remove their longer arms from contact with the connectors, which is frequently necessary in the manipulation of the loom.

25 Figure 1 in side elevation represents a sufficient portion of the head motion of a shedding-forming mechanism of a loom to enable my invention to be understood; and Fig. 2 is a perspective detail showing one of the elbow-levers and a connector, together with the device employed for simultaneously turning all said elbow-levers.

A represents part of the arch or upper portion of the framework of a loom, and A' an 35 attached portion that sustains the cylinder-gears B'. The portion A' has a rod C, on which is fulcrumed a series of vibrator-levers C', each one supporting on a pivot C², extended from the side thereof, a vibrator-gear D, 40 having a crank-pin D', adapted to be turned in one and then in an opposite direction by one or the other of the continuously-rotating cylinder-gears according to the indications of the pattern-surfaces sustained by the pattern-shaft E, one end of which is represented in Fig. 1. Each crank-pin D' has pivoted to it one end of a connector F, the opposite end of which is slotted (see Fig. 2) to embrace a stud

F', extended from the side of the notched harness-controlling lever G, mounted to be 50 turned freely about a fulcrum G². The parts so far described are common to the patent referred to, as is also a locking device adapted to engage the inner free ends of the vibrator-lever, said locking device not being herein 55 lettered or particularly described. In accordance with my invention I have erected on the arch A lugs a, that receive a rock-shaft a'. This rock-shaft receives and forms a fulcrum for a series of elbow-levers H, one only shown 60 in Fig. 2, said levers having a long arm h and a short arm h', the downturned inner end of the long arm being grooved to rest on and embrace the upper edge of the connector F. (See Fig. 1.) The short arm of each elbow-lever has attached to it a draw-spring h², the opposite ends of each draw-spring being connected with a finger h³, rising from a bar h⁴, attached to the arch or other part of the loom-frame by suitable bolts h⁵. The draw-springs 65 acting on the short arms of the elbow-lever keep the inner ends of the longer arms of said levers pressed upon the upper sides of the connectors, so that whenever the indications or projections of the pattern-surface retire 70 from under the vibrator-levers the spring, acting through the elbow-levers and the vibrator-gears, will cause the said gears and the vibrator-levers to descend substantially instantly, so that the leading tooth of the vi- 75 brator-gear next to be engaged by the teeth of the cylinder-gear may be correctly engaged with the teeth of said latter gear to cause a complete and proper movement of the vibrator-gear, and consequently of the harness-lever connected therewith. The action of this elbow-lever is more fully described in an application filed by me January 18, 1904, Serial 80 No. 189,456.

In running looms of this class it is frequently necessary to raise and hold out of action for a longer or shorter period the elbow-lever and to remove the same from contact with the connector—as, for instance, when a connector vibrator-gear and vibrator-lever 95 need to be changed or when a harness-lever

has to be removed. To effect the simultaneous removal of the elbow-levers from contact with the connectors, I have added to the loom what I shall designate as a "releasing" device, it being represented as a plate d , having cam-slots d' , that embrace studs or guides d^2 . When the releasing device is pulled out by the engagement of its handle d^3 by the operator into the position Fig. 2, the releasing device has also imparted to it a bodily lateral movement, causing the outer edge of said releasing device to contact with the short arms of the series of elbow-levers and turn them on or with the rock-shaft d' , such turning of the elbow-levers removing the ends of their longer arms from contact with the connectors, that whatever is desired to accomplish during the removal of the elbow-levers from the connectors may be done. When the releasing device is moved inwardly from its position, Fig. 2, the said releasing device is moved bodily laterally toward the vibrator-gears, thus permitting the spiral springs connected with each one of said elbow-levers to turn said elbow-levers so that the ends of their longer arms descend upon and rest in a yielding manner upon the tops of the connectors. I believe I am the first to provide an independent releasing device capable of being moved when the loom is in motion or at rest to simultaneously elevate all of the levers or other devices that act to produce pressure upon the upper side of the connectors to effect the engagement of the teeth of a vibrator-gear with the teeth of a cylinder-gear, and

hence I desire to claim this feature of my invention broadly.

Having fully described my invention, what I claim as new, and desire to secure by Letters Patent, is—

1. In a loom having a harness-lever, a vibrator-lever, a vibrator-gear, and a connector intermediate said vibrator-gear and harness-lever, a series of spring-controlled devices contacting normally in the running of the loom with the upper sides of the connectors, and a device independent of the vibrator-levers and vibrator-gears to move said spring-controlled devices out of contact with said connectors. 40

2. In a loom, a vibrator-lever, a vibrator-gear pivotally mounted thereon, a harness-lever, a connector uniting said vibrator-gear and harness-lever, a series of elbow-levers, the longer arms of which contact normally during the running of the loom with the upper sides of said connectors, a series of draw-springs connected with the shorter arms of said elbow-levers, and means independent of the vibrator-levers and connectors to simultaneously turn all said elbow-levers that their inner longer arms may be removed from contact with said connectors. 50

In testimony whereof I have signed my name to this specification in the presence of two subscribing witnesses. 55

RANDOLPH CROMPTON.
